UNITED STATES PATENT OFFICE.

FRED F. BOYCE, OF PORTLAND, AND CHARLES B. RUTLEDGE, OF SOUTH PORTLAND,
MAINE.

PROPELLER.

Application filed June 29, 1923. Serial No. 648,633.

To all whom it may concern:

Be it known that we, FRED F. BOYCE and CHARLES B. RUTLEDGE, citizens of the United States, residing at Portland and 5 South Portland, in the county of Cumberland and State of Maine, respectively, have invented certain new and useful Improvements in Propellers, of which the following is a specification.

10 Our invention relates to feathering and reversing propellers of that class in which the blades are disposed around a central hub and thrown from their normal or forward position into their reversing position 15 or into the feathering position by having each blade freely rotate on the hub of the blade.

Our invention is designed particularly as an improved construction of the propeller shown in Patents No. 938,291, dated 20 Oct. 26, 1909, and No. 993,126, dated May 23, 1911.

In the above named patents, the shaft was provided with spherical hub having a 25 groove therein.

The blades were journaled in the casing with a pin engaging the groove in the spherical hub. When the blade moved from one position to the other the pin passed 30 along the groove in the spherical hub.

This construction while it accomplished the result desired, namely twisting the blades from the forward to the reverse position, it was a difficult and expensive construction to build and the pins sliding in the groove were subject to considerable friction 35 so that the motion was not smooth. The shifting of the blades when in certain positions was liable to be checked by the friction 40 of the pin.

Our invention consists in substituting for the spherical hub with its groove and the pin connecting with the propeller blades a simple mitre or bevel gear attached to the 45 shaft and a like gear on the inner end of each of the blades engaging the main gear whereby the blades are rotated into their several positions by the water pressure.

Stops are provided for limiting the rotation of the blades in the two opposite directions.

We have illustrated our invention in the accompanying drawing in which:

Fig. 1, shows a plan of a two bladed pro-

peller with the central portion shown in 55 central horizontal section.

Fig. 2 is an end elevation looking from the extremity of one of the blades towards the center.

Fig. 3 is a face view of the inner end of 60 the propeller blade with its bevel gear and,

Fig. 4 is a portion of the section shown in Fig. 1 including the sleeve with its bevel gear.

Referring to the drawing, 1 represents 65 the tapering sleeve which is keyed or otherwise secured to the rear end of the shaft.

At the forward end of the sleeve 1 is formed a mitre or bevel gear 2 which we call for convenience the "main" bevel gear. 70

Surrounding and inclosing the main bevel gear and the sleeve 1 is a casing 3 preferably with a horizontal joint separating it into two parts this joint being indicated by the dotted line 3' as shown in Fig. 2. 75

The two halves of the casing 3 when placed together form at the two ends two annular hubs 5 and 6, the hub 5 fitting closely around the rear end of the sleeve 1 and the hub 6 fitting around the forward end of the sleeve. Both the two part hub 5 and 6 are screw-threaded and on each is screwed a ring. The ring 7 is screwed on the hub 5 and the ring 8 on the hub 6 thus holding the two parts of the hub together. 85

Formed in the casing 3 laterally of the sleeve 1 are bearings 9, as here, shown two in number, in which are journaled the inner ends of the blades 10. 90

Immediately outside of the bearings 9 the shank of the blade is enlarged to form a shoulder or collar which forms a bearing in the body of the casing and forms the surface on which it rotates and rests. Immediately within the cylindrical surface 14 of the blade which rotates within the bearing is formed the bevel gear 15 which engages the bevel gear 2 on the sleeve or shaft. 95

The gear 15 is not a complete gear, as only a portion of it is used since the blade only rotates from its forward or normal position around to its reversed position or 180 degrees more or less. 100

For the purpose of checking or stopping the blades of the propeller in the normal or forward driving position, stops are 105

formed on the casing adjacent to the shank with corresponding stops on the blade adapted to come in contact with them.

5 Stops 16 and 17 are formed on the casing and on the blade is formed the stop 18.

When the blade is rotating in the direction shown by the arrow in Fig. 2 the stop 18 comes in contact with the stop 17. The blade is then in its forward driving position.

10 When on the other hand the propeller is rotated in the opposite direction the other end of stop 18 comes in contact with stop 16. The propeller is then in the reverse position.

The total rotation to get the blade from 15 one position into the other position is approximately 180 degrees or half a turn.

The blades are made so the amount of surface on the two sides of the center line of rotation are unequal and so that the pressure 20 of the water on the blade as the shaft turns will tend to twist the blade into its forward driving position when the shaft is turning in one direction and into the reverse direction by the operation of the gears.

25 Also when the shaft is not turning as when a sailing vessel is sailing without using the propeller the blades will turn to the feathering position where the edges of the blade are presented to the water.

30 A propeller built according to my invention is much more cheaply made as standard

mechanical motions are used and the blades turn more readily from one position to the other than when made in the old way set out in the patents above cited.

35

We claim:—

1. In a feathering and reversing propeller the combination of a shaft, a main bevel gear thereon, a casing inclosing said gear and connected to rotate with said shaft and said 40 casing having laterally of said shaft a plurality of bearings, propeller blades having their inner ends journaled in said bearings and each blade projecting more on one side of the center line than the opposite side, each 45 of said blades having a bevel gear on its inner end engaging said main bevel gear, and stops for holding said blades in their go-ahead and reverse positions.

2. A feathering and reversing propeller 50 the combination of a shaft, a main bevel gear thereon, a casing inclosing said gear and having laterally of said shaft a plurality of bearings, propeller blades having their inner ends journaled in said bearings 55 and each having on said inner end a bevel gear engaging said main bevel gear, and stops on the outside of said casing for holding the blades in their go-ahead and reverse positions.

FRED F. BOYCE.

CHARLES B. RUTLEDGE.
